AQUARIUM PUMP MOTOR HOUSING

Mervin F. Roberts, Basking Ridge, N.J., assignor to
T.F.H. Publications, Inc., Jersey City, N.J., a corporation of New York

Filed Mar. 31, 1967, Ser. No. 6,476

Term of patent 14 years

(Cl. D65—1)

FIG. 1

FIG. 2

FIG.3

FIG. 1 is a perspective view of the aquarium pump motor housing, the unseen side being a mirror image of that shown;

FIG. 2 is a rear elevational view of the motor housing; and

FIG. 3 is a bottom plan view of the motor housing.

The dominant features of my design reside in the portions shown in full lines.

I claim:

The ornamental design for an aquarium pump motor housing, as shown and described.
